UNITED STATES PATENT OFFICE.

CHARLES E. GLAZIER, OF HORNELLSVILLE, NEW YORK.

SPRAY-NOZZLE.

SPECIFICATION forming part of Letters Patent No. 226,060, dated March 30, 1880.

Application filed April 4, 1879.

To all whom it may concern:

Be it known that I, CHARLES E. GLAZIER, of Hornellsburg, in the county of Steuben and State of New York, have invented a new and Improved Spray-Nozzle, of which the following is a specification.

My invention relates to a spray-nozzle for hose and other water-pipes; and it consists in a certain novel construction and arrangement 10 of devices for breaking up the stream of water and converting it to spray without back-pressure on the column.

The construction will be particularly described in connection with the accompanying 15 drawings.

Figure 1 is an end view of the nozzle. Fig. 2 is a longitudinal section on line xx of Fig. 1. Fig. 3 is a cross-section on line yy of Fig. 2.

Similar letters of reference indicate corresponding parts.

A is a water-pipe, formed at its discharge end with an eye, a , and spring-latch b , for connection of nozzle B, as shown; or the nozzle may be attached by other devices which permit its removal.

The nozzle B consists of a conical shell, c , that flares outwardly from the base that is upon the end of pipe A. Near the outer end of the shell c is attached a number of rods or 30 wires, d , that curve outwardly and converge to a central ring or frame, e , which is held in place by rods d . The ring e is crossed by bars f , and supports by lugs g a tapering ring, h , in a position above the discharge-open-

ing of the pipe A. The aperture of ring h is 35 of smaller diameter than pipe A, and the end toward the pipe is formed as a knife-edge.

The stream of water discharged from pipe A is first divided by ring h . The central portion passes through ring h to ring e , and by 40 ring e and rods d is broken up and deflected sidewise. The water that passes outside of ring h is thrown against the flaring sides of the shell c , then thrown forward, and is broken by bars d . By these means the stream is finely 45 broken up and discharged in a fine spray or rain from the mouth of the nozzle, and with a tendency to spread more or less, according to the force.

The construction described effects the spray- 50 ing without back-pressure on the column.

The spray-nozzle can be applied to hose-pipes, to fixed water-pipes and fountains, and wherever available.

Having thus described my invention, I claim 55 as new and desire to secure by Letters Patent—

The combination of the rings h e , connected by lugs g , the wires d , curving outwardly and then converging toward each other, and the 60 outwardly-flaring shell c , as shown and described, whereby the whole stream is broken into spray.

CHARLES E. GLAZIER.
